UNITED STATES PATENT OFFICE.

GEORG SPIESS, OF LEIPZIG-REUDNITZ, GERMANY.

PRINTING-MACHINE.

1,110,723.

Specification of Letters Patent. Patented Sept. 15, 1914.

Application filed March 7, 1913. Serial No. 752,744.

To all whom it may concern:

Be it known that I, GEORG SPIESS, a subject of the Emperor of Germany, residing in Leipzig-Reudnitz, Germany, have invented 5 certain new and useful Improvements in Printing-Machines, of which the following is a specification.

The printed matter in business books such as ledgers and the like has hitherto been 10 produced in two separate stages inasmuch as the heading of all sheets is produced in one printing operation and the foot on each sheet in a separate or second printing operation.

Attempts have already been made to print 15 the head and the foot on a sheet in one single operation simultaneously, but it was found that too large a fundament or platen became necessary for that purpose.

Since business books of the kind referred to are as a rule of exceptionally large size, 20 it was inconvenient for the sake of printing say only one line at the top and one line at the bottom of such sheets to mask the greatest portion of the platen, because this manipulation necessitates an excessive amount of labor and time particularly in connection with cylinder presses.

Moreover, considerable inking losses had 25 to be put up with, since high speed presses for such large printing forms must necessarily be provided with a correspondingly large inking device. If it is further considered that high speed presses generally require 30 for their working three to five horse-power and for their attendance a person who as a rule must be experienced and therefore demands a relatively high wage, it is evident that for the purpose of printing business

books where only a top and bottom line on 40 each sheet are necessary the method referred to would be rather extravagant. Now this inconvenience arising out of the old method would be the more accentuated the smaller 45 the surface to be printed and since a large number of business books are now produced in small sizes it may be assumed that about 70% of the whole production of business books would have to be effected in a most 50 uneconomical manner. These drawbacks are

to be overcome according to the present invention by the arrangement on the printing head or die of the machine of different printing forms which are located side by side and are alternately put into action. 55

The invention is illustrated by way of example in the accompanying drawings in which: Figure 1 shows a front elevation and Fig. 2 a side elevation of a printing machine constructed in the improved manner. Figs. 60 3, 3^a, and 3^b indicate separately the position of the printing forms with regard to the masking sheet and to the sheet to be printed. Fig. 4 is a partial front view and Fig. 5 a partial plan of a portion of the press on a 65 larger scale. Fig. 6 is a partial elevation of a somewhat modified form. Fig. 7 shows in elevation the operating mechanism for the inking device. Figs. 8 and 9 illustrate in lateral elevation the sheet feeding mechanism. Figs. 10 and 11 show in detail in elevation and plan view respectively the device for preparing the masking sheet. 70

In the constructional example shown the sheets A to be printed are fed individually 75 by any known feeding device against a retractable stop and suitably registered, after which they are placed on the platen C and moved forward until they are in contact with the retractable stop D. In this position the first impression is made by producing for instance the head of the "debit" side. The sheet is then mechanically moved to the next stop in which position it receives the second imprint or the foot of the "debit" 85 side. Where the accounts are divided the stops of course would have to be adjusted accordingly. 80

For the purpose of inking the printing forms F and G an inking device is arranged 90 on a suitable slide which is provided with teeth adapted to engage with the teeth of a toothed segment whereby it receives a reciprocatory movement, as will hereinafter be more specifically described. 95

The forms F and G for printing the head and foot are located side by side on the die E. Between this die and the platen C is a frame H which is movable and serves as a carrier of a sheet of paper or like material. 100

The displacement of this frame is effected by means of a bell crank lever I which is operated by a cam K.

The frame H is always so adjusted that 5 the printing form which should not make an impression on the sheet is caused to descend on the masking sheet R in the frame H, thus producing an impression on the latter sheet, whereas the other printing form is 10 free to pass through the frame or masking sheet and produces the required impression on the sheet to be printed.

The masking sheet R which is suitably fixed or stretched within the frame H may, 15 if desired, be provided with suitable openings according to whether two or more printing forms are required to pass therethrough.

The position of the printing forms with 20 regard to the frame H and the sheet A to be printed will be clearly understood from an inspection of Figs. 3, 3^a and 3^b. The printing forms F are in this case supposed to pass freely through the openings R' in 25 the frame H or the masking sheet and to make their impression on the sheet A located underneath, whereas the printing forms G are, as will be seen arranged between the openings R' and S so that their 30 impression is masked by the frame H and is therefore not made on the sheet A. If it were desired to have the positions changed so as to enable the forms G to make an impression on the sheet A the frame H would 35 be advanced until its openings S register with or are located immediately beneath the forms G. The sheet A, however, is advanced beneath these openings S until the required parts are situated beneath them 40 when the second forms may be caused to descend on the paper. For this second printing position on the sheet A retractable stops may be arranged to which the sheet may be 45 conveyed by suitable bands or other known convenient devices.

It will therefore be seen that the printing of the head and foot on account sheets of business books may thus be effected during one single passage of the sheet through the 50 machine, since the sheet is mechanically advanced and at the same time the masking sheet owing to the adjustment of the frame H is caused to mask one or the other of the printing forms.

55 In the place of a masking sheet provided with openings or cut out portions individual paper strips may, if desired, be arranged in the frame H of only such width as will be necessary to alternately mask one or the 60 other printing form F or G. The fixing of the masking sheet R itself may conveniently be effected by elastic springs S' or other elastic means, as shown for instance in Figs. 4 and 5. It will be seen that when the mask-

ing sheet thus held is brought between the 65 printing forms and the platen C it will receive the impression from the masked printing form while pressed down on the sheet A underneath it preventing the latter, however, from receiving the impression. Thus 70 the masking sheet not only receives the impression from the printing form, which should not print on the sheet A, but it also holds the latter sheet firmly down on the platen while the other printing form produces its impression thereon. 75

In the particular example illustrated in Figs. 4 and 5, the frame H is supported on coil springs T so that it may rise to its initial position immediately the printing die 80 is drawn up by the machine.

In the constructional form shown in Fig. 6, the printing forms F and G are arranged in a similar manner on the die E as before. The platen C is in this case provided with 85 a divided portion consisting of two parts M and N which are vertically adjustable. Their adjustment in the vertical direction is effected by a sliding wedge O which is connected to a rocking arm P. In Fig. 6, the 90 section M is shown raised and it will be understood that the sheet inserted at this point would receive the impression only from the printing form F. To enable the printing form G to print and at the same 95 time to mask the printing form F the wedge O is drawn back until the platen section N has risen above the section M. Thus also with this constructional form it is possible to print the head and foot of a sheet 100 in a single passage of the sheet through the machine, at different points alternately and it is quite immaterial whether the sheets are large or not and how far the impressions are distanced one from the 105 other.

In order to enable the inking rollers to be thrown out of action, when it is desired not to ink the printing forms a special 110 adjusting arrangement is provided, as shown in Fig. 7. The toothed segment Y already referred to and adapted to move the inking carriage X is driven from a cam U with the aid of a double armed lever Z. This lever, however, does not directly engage with the segment Y, but transmits its movement through an intermediate lever 1. This lever 1 is provided with a coupling hook 2 which is under the influence of a 120 spring 3. The double armed lever Z carries a pin 4 working in a slot 5 in the lever 1. So long as the pin 4 moves freely within the guide slot 5, the inking device is not actuated, but as soon as the pin 4 reaches its highest position it is engaged by the coupling hook 2, after which the movement of the lever Z is transmitted to the segment Y 125 and consequently to the inking carriage.

In machines of the kind referred to, several registering stops are required for adjusting the sheet to be printed, and these stops, as will be presently described, are 5 brought into action consecutively.

As shown in Fig. 8, three such stops D', D² and D³ are provided. The stop D' is attached to a rocker 6, D² to a rocker 7, and D³ to a rocker 8. All three rocking arms 10 are rotatable about one single pivot 9 and in their highest position are held by springs 10. Suitable projections 11 on these rocking arms extend into the path of respective cams arranged on a cam disk 12. The 15 cams on this cam disk are so arranged as to cause the cams during one revolution of the cam disk to actuate the rocking arms successively and thereby to withdraw the stops D', D² and D³ consecutively.

In printing machines of this kind, moreover, the sheet to be printed must be advanced intermittently and to this end a device as shown by way of example in Fig. 9 20 is by preference employed according to this invention. The sheet A as it comes from the pile is fed by the feed roller B, first of all to the first stop D', in which position the first impression is produced. Immediately after this operation the sheet is fed 25 successively against the stops D² and D³, for enabling the next following impressions to be produced at different points on the sheet. To this end I provide on an axis 30 13 a rocking arm 14 with a second arm 16 on the same shaft 13 which by means of a link 17 is connected to a double armed lever 18. The latter carries a roller 19 which is in contact with the circumference of a cam disk 20. This cam disk is mounted on a 35 shaft 21 rotating at half the speed of the main driving shaft. Several such cam disks are arranged on shaft 21, that is to say, as many as there are stops or stages through 40 which the sheet is to be advanced. According to the number of cams, the lever arm 18 during one revolution of the shaft 21 will be rocked repeatedly and this movement is transmitted to the arm 16 and the shaft 13 and consequently to the roller 15 which 45 every time is thus caused to descend into contact with the feed roller B and advance the sheet A, as will be readily understood.

In order to facilitate the preparation of the printing support and thereby to save as 50 much time as possible, it is preferable to make use of a preparatory carrier, a construction of which is shown by way of example in Figs. 10 and 11. This carrier 22 which is to be interposed between the platen 60 C and the printing die E consists of cardboard or some other stiff material. This carrier or a sheet stuck on to it is then used to receive the first impression. It is then withdrawn from the machine and tissue

paper or other known means are used to 65 cover up those parts of the impression which are blurred or not clear enough. This being done the carrier is reinserted in the machine with a covering sheet above it, which may, for instance, be glued with its forward edge 70 to a plate 23 and now the printing may take place. The use of a special carrier of this kind enables the preparatory work to be carried out outside of the machine in the most precise and quick manner. 75

What I claim and desire to secure by Letters Patent is—

1. In combination in a printing machine of the class described, a printing head, a plurality of printing forms located side by 80 side and stationary thereon, means for alternately rendering ineffective the printing forms independently thereof, and means for bringing said printing forms into printing operation at different points on the sheet to 85 be printed during a single passage thereof through the machine.

2. In combination in a printing machine of the class described, a printing head, a plurality of printing forms thereon, a 90 platen, masking means for alternately rendering ineffective the printing forms, and sheet feeding means for bringing said printing forms into printing operation at different points on the sheet to be printed during 95 a single passage thereof through the machine.

3. In combination in a printing machine of the class described, a printing head, a plurality of printing forms thereon, a platen, 100 a withdrawable carrier thereon, and masking means operable alternately upon the printing forms.

4. In combination in a printing machine of the class described, a printing head, a plurality of printing forms thereon, a platen, an oscillatory frame between the head and the platen, and a masking sheet carried by 105 said frame for allowing only one printing form to print at a time. 110

5. In combination in a printing machine of the class described, a printing head, a plurality of printing forms thereon, a platen, a frame between the head and the platen, a masking sheet, and elastic suspending 115 means for suspending said sheet from said frame.

6. In combination in a printing machine of the class described, a printing head, a plurality of printing forms thereon, a platen, 120 masking means for said forms, and means for controlling the advance movement of the sheets to be printed comprising a cam disk, a plurality of rocking arms actuated by said disk, and stops on said arms. 125

7. In combination in a printing machine of the class described, a printing head, a plurality of printing forms thereon, a platen,

masking means for said forms, and means
for intermittently advancing the sheet to
be printed comprising a sheet feeding roller,
a cam shaft, a feed roller, and means oper-
ated by said cam shaft for moving the feed
5 roller in and out of contact with the sheet
feeding roller.

In testimony whereof I have affixed my
signature, in presence of two witnesses.

GEORG SPIESS.
